CLAIM

The ornamental design for a folding photographic camera or similar article, as shown and described.

DESCRIPTION

FIG. 1 is a front and top-right perspective view of a folding photographic camera or similar article showing our new design in the open position;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof;
FIG. 7 is a top plan view thereof in closed position;
FIG. 8 is a front elevational view of FIG. 7;
FIG. 9 is a bottom plan view thereof;
FIG. 10 is a right side elevational view of FIG. 7;
FIG. 11 is a left side elevational view of FIG. 7; and
FIG. 12 is a rear elevational view of FIG. 7.
